DESIGN FOR A TEXTILE FABRIC OR SIMILAR ARTICLE OF MANUFACTURE

Application filed October 19, 1932. Serial No. 45,409. Term of patent 3½ years.

To all whom it may concern:

Be it known that I, ALFRED J. HEINKE, a citizen of the United States and resident of Towaco, in the county of Morris and State of New Jersey, have invented a new, original, and ornamental Design for Textile Fabric or Similar Article of Manufacture, of which the following is a specification, reference being had to the accompanying drawing, forming a part thereof, and showing a face view of a piece of textile fabric embodying my design, the shading indicating contrast in color. A repeat unit is shown in the figure. The re-

peat occurs on a line parallel to the side, and on a line diagonal to the bottom of the drawing. The lines A and B appearing on the drawing are placed there to facilitate following the unit.

I claim:

The ornamental design for a textile fabric or similar article of manufacture substantially as shown and described.

Signed at New York, in the county of New York and State of New York, this eighteenth day of October A. D. 1932.

ALFRED J. HEINKE.
